(57) **CLAIM**

The ornamental design for a cooking vessel handle, as shown and described.

DESCRIPTION

FIG. 1 is a perspective view of the handle.

FIG. 2 is a front elevational view of the handle.

FIG. 3 is a rear elevational view of the handle.

FIG. 4 is a top view of the pot handle.

FIG. 5 is a bottom view of the handle.

FIG. 6 is a right side view of the handle.

FIG. 7 is a left side view of the handle; and,

FIG. 8 is a reduced perspective view of the handle attached to a cooking vessel.

The broken lines shown in FIG. 8 represent the environment in which the design resides and forms no part of the claim.
